(57) **CLAIM**

The ornamental design for a stand for speaker, as shown and described.

DESCRIPTION

FIG. 1 is a perspective view of the front, top and right side of a stand for speaker showing my new design;

FIG. 2 is a front view thereof, and a rear view is a mirror image of the front view;

FIG. 3 is a left side view thereof, and a right side view is a mirror image of the left side view;

FIG. 4 is a top view thereof; and,

FIG. 5 is a bottom view thereof.

1 Claim, 5 Drawing Sheets---
